MOUNTING BRACKET FOR BATHROOM FIXTURES

Andrew J. Unetic, Santa Ana, Calif., assignor, by mesne assignments, to The Yale and Towne Manufacturing Company, New York, N. Y., a corporation of Connecticut

Application March 4, 1957, Serial No. 45,085

Term of patent 14 years

(Cl. D4—3)

Fig. 1 is a perspective view of a mounting bracket for bathroom fixtures showing my new design;

Fig. 2 is a top plan view;

Fig. 3 is a front elevational view;

Fig. 4 is a side elevational view; and

Fig. 5 is a bottom plan view.

I claim:

The ornamental design for a mounting bracket for bathroom fixtures, as shown.
